TRAFFIC LANE MARKER STRIP

John E. Carter, Columbus, Ohio

Application May 18, 1946, Serial No. 670,792

14 Claims. (Cl. 94—1.5)

1

My invention relates to a traffic lane marker strip fitting flush with the surface of a concrete roadway, and more particularly pertains to an elastomer covered metal lane marker strip which is fastened to dowel bars and vertical joint sealing strips between concrete slabs, in a waterproof manner, so that the marker strip may follow a vertical joint between concrete slabs and be fastened to the dowel bars, without interfering with the water-proof nature of the joint.

My invention also relates to discs, or squares, of metal covered with elastomeric material, which discs or squares may be secured to said roadway to form spot traffic markers.

The principal object of my invention is to provide a traffic lane marker strip for a concrete slab roadway, which strip is secured to the roadway, flush with the surface, and which strip has water sealing connections to a dowel bar assembly, and vertical waterproof joint sealing means in the roadway.

A further object of my invention is to provide a traffic lane marker strip which is adapted to lie along the longitudinal vertical joints in a concrete slab road, which strip is secured to the concrete slabs, and which strip has water sealing connections therewith, and with joint sealing means interposed between the slabs forming the vertical joints.

Another object of my invention is to provide a novel lane marker in the form of a disc spot or square spot which may be secured to said roadway at intervals, flush with the surface of the pavement, to form a visible traffic mark.

Further objects and objects relating to details of construction and economies of operation will definitely appear from the detailed description to follow. I have accomplished the objects of my invention by the devices and means set forth in the following specification. My invention is clearly defined and pointed out in the appended claims. Structures forming the preferred embodiments of my invention are illustrated in the accompanying drawings forming a part of this specification in which:

Fig. 1 is a plan view of a part of two concrete slabs showing my elastomer covered metal traffic lane marker set flush with the road surface along the longitudinal vertical joints between the slabs, with the dowel bar assembly showing in dotted line, and with a part of the concrete broken away, showing my elastomer topped lane marker and dowel bar assembly in full lines.

Fig. 2 is a vertical sectional view taken along the line 2—2 of Fig. 1.

2

Fig. 3 is a detail, sectional view showing the lane marker assembly taken along the line 3—3 of Fig. 1.

Fig. 3a is a detail, sectional view showing the joint sealing strip, the lane marker, and the dowel bar connection taken along the line 3a—3a of Fig. 1.

Fig. 3b is a view in perspective of the joint sealing strip and side plates, showing the cut-away portion in the joint sealing strip and plates for receiving the dowel bar and marker strip connections.

Fig. 4 is a detail, sectional view of one form of the replaceable individual spot type of lane marker and means for receiving it in the concrete.

Fig. 5 is a detail, sectional view of another form of the replaceable individual lane marker and means for securing it in the concrete.

Fig. 6 is a detail, sectional view taken along the line 6—6 of Fig. 1.

Fig. 7 is a detail view in perspective of the disc of the disc type of individual spot marker.

Fig. 8 is a detail view in perspective of the square of the square type of individual spot marker.

Fig. 9 is a detail view in perspective of one of the dowel bar casings.

Fig. 10 is a detail view in perspective of one of the rubber unions for water-sealing the dowel bar casings and the associated T.

Fig. 11 is a detail view in perspective showing the elastomer covered metal lane marking strip.

Fig. 12 is a detail view in perspective showing the T, which is used to connect the marking strip to a dowel bar.

Fig. 13 is a detail view in perspective showing a metal collar adapted to fit around a screw fastening the lane marking strip to a T connection embracing a dowel bar.

Fig. 14 is a detail view in perspective showing a rubber sleeve adapted to fit around the metal collar shown in Fig. 13.

Fig. 15 is a detail view in perspective showing an elastomeric sleeve adapted to fit around a rubber union such as is shown in Fig. 10.

Fig. 16 is a detail view in perspective of a typical dowel bar with a helical lubricating groove cut on its exterior surface.

Fig. 17 is a detail view in perspective of a screw shown in section in Figs. 4 and 5.

Fig. 18 is a detail view in perspective of the screw receiving lag bolt shown partly in section in Fig. 4.

Fig. 19 is a detail view in perspective of the

screw receiving lag bolt shown partly in section in Fig. 5.

Fig. 20 is a detail view in perspective of the screw shown in section in Fig. 3.

Fig. 21 is a perspective view of a locking washer 5 against which the end of the screw of Fig. 20 abuts.

In the drawings the same reference numerals refer to the same parts throughout the several views, and the sectional views are looking in the 10 direction of the arrows at the ends of the section lines.

In general, my invention relates to a traffic lane marker strip comprising a metal base and a tough, resilient, and water-proof, elastomeric 15 cover secured to said base, which strip is intended to be secured flush in the surface of a roadway. The lane marker is provided with means for securing it at intervals to the dowel bars of an expansion joint assembly which is positioned in 20 the vertical joints between concrete slabs which form the pavement on a roadbed. My lane marker is adapted to be superimposed over the vertical joints of the concrete slabs, above a joint sealing strip which extends between the faces of 25 the adjoining slabs, and through which dowel bars pass. The joint sealing strip is provided with an aperture at each dowel bar unit location for accommodating connections for securing the marking strip to the associated dowel bar. The 30 joint sealing strip is made of elastomeric material provided with air pockets therein to form a resilient and compressible water-proof vertical joint, and is provided with means cooperating with dowel bar units passing therethrough in water-sealing manner, to permit of expansion and contraction of the slabs. The connections for securing the lane marking strip to a dowel bar, include a T through the head of which the 35 dowel bar passes, a metal sleeve surrounding a screw projecting through a hole in the lane marker strip, which screw is screwed into the shaft of the T, and a water-proof investment therefor.

Each dowel bar is slidably mounted in a concrete-held casing on each end. Because the dowel bar casings are buried in the concrete, the casings with the dowel bar therein are supported on the roadbed, prior to the pouring of concrete thereon, by means of chairs. Each dowel bar near its middle and between the casings, projects through the head in the associated T. The casings each are provided with a groove on the inner end, adapted to receive one end of an elastomeric, water-proof union. The other end of such a rubber union is adapted to be received by a formation on the adjacent end of the head of the associated T. A water-proof, elastomeric sleeve surrounds each union. Thus, a water-tight connection is provided between the T and each of the two associated casings, which thoroughly water-proof the enclosed dowel bar.

The screw, piercing the marking strip and screwed into the shaft of the T, is surrounded by a metal collar, which in turn is invested by an elastic and compressible rubber sleeve which abuts against the rubber sleeves surrounding the associated rubber unions. The rubber sleeve surrounding a collar makes a water-tight seal with the vertical sealing strip connection aperture.

Referring to the drawings, a roadbed 11 (Fig. 3) is provided for concrete pavement slabs 10 and 10a (see also Fig. 1). Embedded in the roadbed are wire staples 23 holding the lower member of dowel bar unit chairs 24 (see also Fig. 2) in

place. The chairs, of which there is one for each dowel bar casing, each have wire uprights formed into a downwardly turning snap loop 24a (Fig. 2) seating the outer grooved end 24b of a dowel bar casing 16 (see also Figs. 3 and 9) to hold the dowel bar units in place prior to the casting of concrete thereabout.

The inner end of each dowel bar casing 16 (Fig. 9) has an annular groove 27 (Fig. 9) adapted to receive one end of the water-proof union 15 (Fig. 10). Each of the casings 16 has an interior bore 28 (Fig. 3) which is adapted to receive one end of a dowel bar 17 (see also Fig. 16), which has a helical lubricating groove 29 on its exterior.

Each dowel bar projects through a passage-way 30 (Fig. 12) of an associated T 14 (see also Fig. 3). Each T 14 has an upwardly projecting shaft 31 (Fig. 12) having internal threads 32 adapted to receive the external threads of a screw 13 (Figs. 3 and 20). The end of screw 13 after passing through a metal spacing collar 21 (Fig. 13) abuts against a lock washer (Fig. 21) shown in the bottom of the threaded hole in the shaft of the T. The lower end of collar 21 abuts the upper end of shaft 31, and the upper end of collar 21 abuts metal strip 12a (Fig. 11) which forms a base for the elastomeric covering 12 cemented or otherwise fastened to its top and sides, forming the unitary lane marking strip 12-12a. At each dowel unit interval, the strip 12-12a is pierced by a hole 12c. The diameter of the hole 12c through the elastomeric covering 12 fits the head of screw 13 and the diameter of the hole in the metal strip 12a fits the shaft of the screw 13. Thus, the longitudinal rubber-topped metal lane marker strip 12-12a is secured to each of the dowel bars in such a manner that it may be removed for replacement.

It is necessary, in lane markers of this type, to provide a means for preventing the entry of water into the vertical joints, as water causes the expansion joint mechanism and the connections between it and the lane marker to become corroded, and causes erosion of and ice damage to the concrete.

I, therefore, provide along the edges of covering 12 of the lane marker strip unit and interior thereof, air channels 12b which permit the expanding movement of the concrete, during periods of high temperature, to be expended in compressing the enclosed air without distorting the elastomer material upwardly to form ridges in the road. On subsequent contraction of the concrete the strip expands keeping the joint tight.

Filling the vertical joint between the concrete slabs, where such joint is not occupied by the dowel bar units, the connections between them 60 and the lane marker strip, and the compressible investment 22, to be described, is a resilient and compressible joint sealing strip 18, set upon the roadbed, before the concrete is cast, between two metal plates 18a and 18b (see Fig. 6), held upright in U-shaped chairs 18c welded to the dowel bar unit chairs. The strip 18 is made of water-proof elastomeric material having air channels 18d running its length to permit compression of it without substantial vertical distortion.

As shown in Fig. 3b, the sealing strip 18 and plates 18a and 18b are provided with an aperture 41, at each of the dowel bar intervals to receive the dowel bar units, the lane marker strip connections, and the investments which enable such connections to withstand the compression move-

ments of the expanding concrete. A resilient and compressible, elastomeric investment 22 (Fig. 14), provided with longitudinal air pockets 22a, is placed over each sleeve 21 and the shaft of each T 14.

The entire assembly of dowel bar units, joint sealing strip, and the lane marker strip and its connections to the dowel bars is put in place on the roadbed prior to the casting of concrete thereover to the height of the top of covering 12.

The water-sealing connections for the union of the casings 16 carrying a dowel bar include the cylindrical elastomeric union or expandible tubular extension 15 (Fig. 10), which has angular shoulders 41 at each interior end, one to be received by the annular groove 27 of the associated casing 16, and the other to be received by the associated flange 43 provided on the T 14 (Fig. 12). The T 14 and the expandible tubular extensions 15 on the opposite ends of the head of the T constitute a dowel embracing sleeve spanning the joint space between the concrete slabs. The union 15 is surrounded by water-proof sleeve 20a, which is of a length equal to that of the union. The circumferential portion of the head of T 14 from which projects shaft 31, and against which the edges of the rubber union 15 in sleeve 20 abut, is received into portion 44 of aperture 41 in the sealing strip 18 and plates 18a and 18b (Fig. 3b), at each assembly point. The investment 22 is received into portion 45 of aperture 41.

Concrete is poured over the joint sealing structure, around the connections, and the marker strip assembly, thus being formed into slabs which lie adjacent to one another but separated by strip 18 and plates 18a and 18b, and which may expand and contract, without damage to the joint sealing strip, the dowel bars, or the lane marking strip assembly.

The rubber topped metal lane marker of my invention may be readily replaced, without in any way injuring the means by which it is fastened to the dowel bars, by merely removing the securing screws.

I provide a modified form of elastomer topped metal lane marker which includes a metal disc topped with elastomeric material bonded thereto, and which is adapted to be secured to the roadway, in a series to form a lane. In Fig. 4 a section through this modification is shown and includes a metal disc 50, topped by an elastomeric covering 51 (see also Fig. 7) extending over the sides. The covering 51 is provided with a hole 52 to receive the head 54 of a screw 53 extending through disc 50, which screwhead abuts the metal disc 50. Screw 53 has a threaded portion which is received by bolt 56 embedded in the concrete.

Another modification shown in Fig. 5, is provided with a square metal member 57, which has an elastomeric covering 58 on top and sides, which receives a screw, similar to screw 53, screwed into a lag bolt 59 embedded in the concrete.

Of the elastomeric materials I have in mind as preferable, butadiene-acrylonitrile copolymer material is eminently suitable when compounded and vulcanized to the tough resilience associated with modern auto tire casings. Next, I prefer natural rubber compounded and vulcanized to the same resilient toughness. I am not, however, limiting my invention to these two specific materials as similar desirable characteristics are found in other commercial elastomeric substances, now available, which, like the two named, are water-

proof in addition to having the resistance to wear and atmospheric aging.

I am aware that the structures herein described are susceptible of considerable variation without departing from the spirit of my invention, and, therefore, I claim my invention broadly as indicated by appended claims.

Having thus described my invention, what I claim as new and useful and desire to secure by United States Letters Patent is:

1. A traffic lane marker assembly for a concrete slab road pavement, including in combination, a dowel bar joining two concrete slabs across a vertical joint between the slabs; said dowel bar being positioned below the surface of the concrete; a traffic lane marker strip laid on the surface of the concrete over the joint; a hollow tubular member including a T and expandible tubular extension embracing said dowel bar and spanning the vertical joint between the slabs; said T having a tubular head and a shaft; and bolt means fastening the traffic lane marker strip to the shaft of the T, whereby the traffic lane marker strip is held in position on the surface of the concrete road, but is releasable from said road by unbolting the strip from the fastening means.

2. A traffic lane marker strip assembly for a concrete slab road pavement, including in combination, a plurality of concrete slabs laid upon a roadbed in adjacent proximity to one another, said slabs being positioned so as to form a longitudinal vertical joint along said roadway; a dowel bar joining adjacent concrete slabs at a plurality of intervals along the longitudinal joint, said dowel bars being positioned in the concrete slabs with which they are associated below the road surface; a traffic lane marker strip laid on the road pavement surface over the longitudinal joint, said marker strip having bolt holes therein at intervals corresponding to the dowel bar intervals and said holes being positioned directly over the associated dowel bars; a hollow tubular connecting means, including expandible tubular extensions spanning the vertical joint between the slabs associated with each dowel bar through which the associated dowel bar is slidably mounted; said connecting means having protruding upwardly at the vertical joint a bolt screw socket; and a bolt for each of said bolt holes in the strip, said bolt being fastenable to the connecting means by threads, whereby when such bolts are passed through the strip and screwed in place in the connecting means the strip is held in place on the roadbed, but may be released therefrom for replacement by unscrewing the bolts from the connecting means.

3. A dowel bar unit assembly for use in connecting adjacent concrete road pavement slabs and a traffic lane marker strip in combination, a dowel bar; a T having a dowel bar aperture in its head in which the midpoint of said dowel bar is slidable, said T having on either end thereof a flange; and said T having its shaft provided with internal screw threads; a dowel bar casing for each end of said dowel bar in which casing the dowel bar is slidable; and each of said casings having on its inner end opposed to the flange of the T in proximity therewith, a flange; and a resilient water-proof union connected to proximate flanges for joining said casings to the T, in water-proof fit.

4. A dowel bar unit assembly for use in connecting adjacent concrete road pavement slabs and a traffic lane marker strip including in combination, a metal dowel bar; a metal T having

a dowel bar aperture in its head in which the dowel bar is slidably movable, said T being positioned at approximately the midpoint of said dowel bar, and said T having a shaft having internal screw threads therein; a water-proof metal casing for each end of the dowel bar, the dowel bar being slidably mounted in said casings; and a water-proof resilient and compressible union joining each casing with the T, whereby said dowel bar is encased entirely against the entry of water, but is in floating condition inside of said casings and T.

5. A dowel bar unit assembly for use in connecting adjacent concrete road pavement slabs and a traffic lane marker strip including in combination, a dowel bar; a water-proof metal casing for each end of said dowel bar in which the dowel bar is slidably fitted; a metal piece surrounding the dowel at its mid-point between the internal end of the casings for connection to the marker strip, said dowel bar being slidably movable in said metal piece; and water-proof, resilient, compressible unions joining said metal piece to the casings on either side thereof, whereby said dowel bar is protected against the entry of water and yet is slidably movable within said casings which may be moved toward one another slightly by reason of the compressible nature of said unions.

6. A dowel bar unit assembly for use in connecting adjacent concrete road pavement slabs and a traffic lane marker strip including in combination, a dowel bar; a metal piece slidably mounted on said dowel bar and positioned near the mid-portion thereof for connection to the marker strip, said piece having a threaded portion in a boss protruding from the mid-portion thereof; a casing for either end of the dowel bar, each end of the dowel bar being slidably mounted in the associated casing, and the interior ends of said casing approximating the metal piece; and a resilient, compressible, and elastic union connecting each casing with the metal piece, whereby said dowel bar floats in said casings and wherein said casings are movable slightly toward one another by reason of the resilience and elasticity of said unions.

7. The traffic lane marker strip of claim 2 including means filling the joint spaces not occupied by the dowel bars and connecting means, said filling means being water-proof and elastic, whereby the joint is rendered water-proof under conditions subsequent to expansion and contraction.

8. In a concrete slab road pavement construction including dowel bars connecting adjacent pavement slabs across the vertical joint therebetween and a traffic lane marker strip laid on the surface of the pavement over the vertical joint, the combination of means connecting the lane marker strip to each of the dowel bars including a tubular sleeve on said dowel bars having expandable tubular extensions for spanning the joint; and means to seal the joint spaces not occupied by the dowel bars and connecting means with water-proof material which is elastic, whereby the joint is sealed against the entry of water therein during subsequent expansion and contraction movements of the concrete slabs.

9. In a concrete slab road pavement construction including dowel bars connecting adjacent pavement slabs across the vertical joint therebetween and a traffic lane marker strip laid on the surface of the pavement over the vertical joint, the combination of a means, including a dowel

bar embracing sleeve, including expandible tubular sections for spanning the joint, engaged by a bolt passing through the strip, for connecting the lane marker strip to each of the dowel bars; and means to seal the joint spaces not occupied by the dowel bars and connecting means against the entry of water.

10. In a concrete slab road pavement construction including dowel bars connecting adjacent pavement slabs across the vertical joint therebetween and a traffic lane marker strip laid on the surface of the pavement over the vertical joint, the combination of a means, including a dowel bar embracing sleeve, including expandible tubular sections for spanning the joint engaged by a bolt passing through the strip, for each of the dowel bars for connecting the lane marker strip to each of the dowel bars; and means to seal the joint spaces not occupied by the dowel bars and connecting means, said sealing means being of resilient and compressible material, whereby upon expansion and contraction of the joint the joint will be protected against the entry of water.

11. In a concrete slab road pavement construction including dowel bars connecting two adjacent pavement slabs across the vertical joint therebetween and a traffic lane marker strip laid on the surface of the pavement over the vertical joint, the combination of a means including a dowel bar embracing sleeve, including expandible tubular sections for spanning the joint engaged by a connector passing through the strip, for connecting the lane marker strip to each of the dowel bars, each of said dowel bars being slidably in said embracing sleeve and said tubular extensions; and elastomeric and compressible shields surrounding the connector and dowel bar embracing means, protecting said connector against the expansion action of the concrete.

12. In a concrete slab road pavement construction including dowel bars connecting two adjacent pavement slabs across the vertical joint therebetween and a traffic lane marker strip laid on the surface of the pavement over the vertical joint, the combination of a means including a dowel bar embracing sleeve, including expandible tubular extensions to span the joint engaged by a connector passing through the strip, for connecting each of the dowel bars to the marker strip, said dowel bars being slidably mounted in the embracing sleeve and tubular extensions with which it is associated; a water-proof casing on each end of the dowel bar; elastomeric and resilient unions engaging each casing with the embracing means cooperating with the associated dowel bar, whereby said dowel bars each are encased in a water-proof manner but floating therein; an elastomeric water-proof and compressible sleeve surrounding each connector and abutting on the top end against the under part of the lane marker strip and on the lower end against the water-proof union connecting the dowel bar casings to the embracing piece; and an elastomeric and compressible joint filling piece

60 of material filling all the space in the joint not occupied by the dowel bars, the connectors, and the water-proof means surrounding them, whereby said joint is protected against the entry of water under normal conditions and during subsequent expansion and contraction of the concrete.

13. A traffic lane marker strip assembly for a concrete slab road pavement comprising the combination of a dowel bar adapted to be embedded in the ends of two adjacent slabs for

Joining them together, a traffic lane marker strip adapted to be laid on the surface of the concrete over the joint between the slabs, a hollow tubular member, including expansible tubular extensions to span the joint between the sections slidably mounted on the dowel bar between the ends of adjacent slabs, and means for clamping the marking strip to the hollow tubular member.

14. A traffic lane marker strip assembly as set forth in claim 13, including a sectional casing for the dowel bar, and means for connecting the hollow tubular member to the sections of the dowel casing.

JOHN E. CARTER.
